UNITED STATES PATENT OFFICE.

ALEXANDER GELSZ, OF PHILADELPHIA, PENNSYLVANIA.

DESIGN FOR THE ORNAMENTATION OF A DRINKING-VESSEL.

SPECIFICATION forming part of Design No. 12,634, dated December 27, 1881.

Application filed October 20, 1881. Term of patent 31 years.

To all whom it may concern:

Be it known that I, ALEXANDER GELSZ, a citizen of the United States, residing in Philadelphia, Pennsylvania, have invented a new and original Design for the Ornamentation of a Drinking-Vessel, of which the following is a specification.

My design for the ornamentation of a drinking-vessel is fully shown in the accompanying drawings, which show the design applied to a tumbler, Figure 1 being a view of one side of the tumbler and Fig. 2 a view of the opposite side of the same.

The design comprises representations in relief or intaglio of portrait busts of the late Presidents Lincoln and Garfield, a representation of a laurel-wreath, *a*, partially surrounding each bust. The upper edge or rim of the tumbler has a black band, *b*, and beneath the same are representations of stars arranged in a row, *d*, the continuity of which is interrupted by the representation of a shield and flags, *f*. Around the tumbler, near the bottom, is a band, *g*, the character of which is too fully shown to need description.

The band *b* may be white instead of black, if desired, and the portrait of President Lincoln may be omitted from the design without essentially changing the character of the same; but it is preferable to include both portraits. 30

I claim—

1. The design comprising the representation of the bust and the border *b*, as shown and described.

2. The design comprising the representation of the bust and the row of stars *d*, as shown and described. 35

3. The design comprising the representation of the bust, the row of stars *d*, and the representation of the shield and flags *f*, as shown 40 and described.

In testimony whereof I have signed my name to this specification in the presence of two subscribing witnesses.

ALEX. GELSZ.
